OIL CRACKING UNIT

Nathaniel O. Harmon, Los Angeles, Calif.

Application May 15, 1946, Serial No. 669,893

15 Claims. (Cl. 196—110)

1

This invention has to do with improvements in oil cracking apparatus of the general type comprising a heating tube through which a flow of oil is maintained under condition permitting variation or control of the thickness of the oil film or stream undergoing cracking. The present application is a continuation in part of my copending application Ser. No. 585,085, filed March 27, 1945, on "Apparatus and process for treating hydrocarbon oil."

My primary object is to provide for accurate and positive control of the thickness of that portion of an oil stream passing through a cracking tube, which is subjected to cracking temperatures by a heating medium applied to the exterior of the tube. Particularly the invention aims to permit definite predetermination of the oil stream thickness by the formation of walls defining the oil conducting space at the inside and outside of the stream, and providing for variation of the transverse dimensions of the space, and therefore of the oil stream, by relative transverse adjustment of the confining walls.

In accordance with the invention, I provide within an externally heated cracking tube an elongated member, preferably in the form of a smaller diameter tube, mounted for transverse or vertical adjustment within and relative to the outer tube. Desirably the oil flow may be limited to the lower portion of the space between the tubes, which space by reason of the adjustability of the inner member, is variable in accordance with the character of the charging stock to correspondingly vary and control the thickness of the oil stream being subjected to cracking temperature. In this manner I assure highly efficient, rapid and uniform heating of the oil stream, with resultant accomplishment of higher oil conversion and less carbon formation than otherwise could be obtainable with less efficient heating, or with such systems as permit localized or excessive over-heating of the oil.

Further in the interests of maintaining maximum heat transfer rates, I preferably employ as the heating medium a molten normally solid material such as lead, or any other suitable metal or salt capable of circulation in molten condition. Constant circulation of for example molten lead, is maintained along the outside of the outer tube, preferably through a jacket confining the heating medium to that lower portion of the tube corresponding to the oil depth.

Various additional features and aspects of the invention might preliminarily be recited at

length, but all these, as well as the objects referred to in the foregoing, will be more readily understood from the following detailed description of a typical embodiment of the invention shown by the accompanying drawing, in which:

Fig. 1 is a vertical cross-sectional view taken longitudinally through the cracking unit;

Fig. 2 is a fragmentary cross-section on line 2—2 of Fig. 1; and

Fig. 3 is a similar view illustrating the variational form of the invention.

While in Fig. 1 I have shown a single cracking unit, it will be understood that a cracking plant may employ any number of such units interconnected for series or parallel flow of the oil through them, depending upon the nature and purposes of the process. Since the invention is primarily concerned with the features of construction in the unit itself, the showing of a single unit will suffice for present purposes.

The unit, generally indicated at 10, is shown to comprise an outer horizontally extending tube 11 terminally connected, as by threaded joints 111, with enlarged chambers 12 and 12a of corresponding form and construction. Each chamber may include a body section 13 attached to the pipe 11, and a removable cover section 14 attached to the body by screws 15. Charging stock to be cracked, is introduced to chamber 12 through the inlet line 16, the oil thence passing through tube 11 wherein it is subjected to cracking and partial vaporization, the unvaporized residue being withdrawn from chamber 12a through the outlet line 17. Vapors are removed from either or both of the chambers through lines 18. Preferably the tube assembly will be inclined toward the right sufficiently to maintain gravity oil flow therethrough at the desired rate.

Tube 11 contains a member 19, which in the broad contemplation of the invention may be of any suitable shape and construction capable of being adjustably mounted to extend longitudinally within and in spaced relation to the outer tube, in a manner permitting variation of the transverse dimensions of the oil passing space between the member and tube, and to correspondingly vary the transverse dimensions of the oil film or stream undergoing cracking. Preferably, member 19 comprises a tube 20, vertically aligned with the tube 11 and spaced therefrom to provide an oil passage or channel 22. Tube 20 may be supported in minimum spaced relation to the outer tube 11 by screws 23 threaded into the inner tube and secured by nuts 23a, the screws having their heads bearing against the bottom por-

tions of tube 11 as best shown in Fig. 2. The top of the tube optionally may contain apertures 21, through which access may be had to the nuts 23a. The screws 23 are adjustable to vary the tube clearance at 22 and therefore the thickness of the oil stream or film passing between the tubes from chamber 12 into chamber 12a. At this point it may be mentioned that the invention contemplates maintaining the oil flow at a rate such that the oil stream will occupy space 22 to a level approximately at the horizontal axial plane of the outer tube 11.

Provision also is made for vertically adjusting the ends of the tube 20 in accordance with the spacing to be maintained at 22, by suitable means, generally indicated at 231, operable at the outside of the chambers 12 and 12a. Typically, each adjustment may comprise an arm 24 projecting from the closed end of the tube and supported on an eccentric 241 carried by shaft 25 extending outwardly through an appropriate seal gland 26. Arm 24 may be confined against such lateral movement as might otherwise shift the tube 20 out of vertical alignment with tube 11, by guide flanges 27 cast integrally with the chamber covers 14 and positioned at each side of the eccentric 241. Upon rotation of shaft 25, as by tool applied to its outer end 28, eccentric 241 is rotated to raise or lower the arm 24, and therefore the corresponding end of tube 20. As will be understood, the eccentric 241 and screws 23 may be designed to provide for any desired minimum clearance at 22 between the tubes, and to permit any predetermined enlargement of that clearance.

Tube 11 is externally heated, preferably by a continuous flow of heating fluid confined to the lower portion of the tube corresponding generally to the oil depth therein. Thus the tube is shown in Fig. 2 to carry a welded jacket 29 extending substantially the length of the tube between the connections at 11. The heating fluid may be passed longitudinally in either direction through the jacket, by way of its terminal pipe connections 30 and 31 which lead to and from a heater, not shown, from which a continuous circulation of the heating medium may be maintained. In view of the importance of maintaining the maximum rates of heat transfer from the heating fluid in the jacket 29 to the wall of the tube 11, I preferably employ as the heating medium, a molten, normally solid material such as lead or a compound containing fusible metallic salts.

For purposes of most efficient operation, the space at 22 is adjusted to reduce the transverse dimension or thickness of the oil stream flowing therethrough, to a degree assuring rapid and uniform transference of heat from the tube wall 11 to all portions of the oil stream. In this manner I avoid excessive or localized over-heating of the oil by assuring its rapid and uniform heating to a closely controllable temperature productive of maximum conversion with minimum carbon formation. The vaporized constituents of the oil flow through the space in the upper interior of tube 11 into the chambers 12 and 12a, and the unvaporized residuum entering chamber 12a is continuously withdrawn through its outlet 17.

Fig. 3 illustrates a variational form of the invention in which the outer tube 34 and heating fluid jacket 35 have essentially the same form as the previously described corresponding parts, but with the shape of the inner member or tube 36 changed from the circular form of tube 20. Here

tube 36 is shown to have a cylindrical or circular cross-section lower portion 36a concentric with the tube 34, and an upper arcuate portion 36b, the curvature of which normally affords somewhat greater clearance at 37 than in the oil passing space 38 below the tube. Because of the concentricity of tube 34 and the lower portion 36a of the inner tube in the position shown, greater uniformity may be maintained throughout the oil passing clearance at 38 between the tubes. As will be understood, the same provisions may be made for effecting vertical adjustments of the tube 36, as previously explained in connection with tube 20 in the first described form.

Oil or vapor condensate are accessible to the interior of tube 20, as through openings 21, and provision may be made for maintaining liquid drainage from the lower end of the tube, as through opening 40 discharging into chamber 12a.

I claim:

1. An oil cracking unit comprising an elongated tube, means for externally heating said tube, a member extending longitudinally inside said tube and spaced therefrom, means for passing oil through the space between said member and tube, and means mounting said member for adjustment to vary the transverse dimensions of said space.

30. 2. An oil cracking unit comprising an elongated tube, means for externally heating said tube, a hollow tubular member extending longitudinally inside said tube and spaced therefrom, means for passing oil through the space between said member and tube, and means mounting said member for adjustment to vary the transverse dimensions of said space.

35. 3. An oil cracking unit comprising an elongated tube, means for externally heating said tube, a member extending longitudinally inside said tube and spaced therefrom, means for passing oil through the space between said member and tube, and adjustable means for varying the position of said member laterally within the tube to vary the transverse dimensions of said space.

40. 4. An oil cracking unit comprising an elongated tube, means for externally heating said tube, a member extending longitudinally inside said tube and spaced therefrom, means for passing oil through the space between said member and tube, and adjustable means for varying the position of said member laterally within the tube to vary the transverse dimensions of said space.

45. 5. An oil cracking unit comprising an elongated tube, means for externally heating said tube, a member extending longitudinally inside said tube and spaced therefrom, means for passing oil through the space between said member and tube, and adjustable means beyond one end of the tube for varying the position of said member laterally within the tube to vary the transverse dimensions of said space.

55. 6. An oil cracking unit comprising an elongated tube, means for externally heating said tube, a member extending longitudinally inside said tube and spaced therefrom, means for passing oil through the space between said member and tube, and adjustable means beyond both ends of the tube for varying the position of said member laterally within the tube to vary the transverse dimensions of said space.

60. 7. An oil cracking unit comprising an elongated tube, means for externally heating said tube, a member extending longitudinally inside said tube and spaced therefrom, means for passing oil through the space between said member and tube, and adjustable means inside the tube for varying the position of said member laterally within the tube to vary the transverse dimensions of said space.

70. 8. An oil cracking unit comprising an elongated tube, means for externally applying heating fluid to the lower portion only of the tube,

a member extending longitudinally inside said tube and spaced therefrom, means for passing oil through the space between said member and tube, and means mounting said member for adjustment to vary the transverse dimensions of said space.

8. An oil cracking unit comprising an elongated tube, a heat conducting fluid jacket carried by the lower portion only of the tube, a member extending longitudinally inside said tube and spaced therefrom, means for passing oil through the space between said member and tube, and means mounting said member for adjustment to vary the transverse dimensions of said space.

9. An oil cracking unit comprising an elongated tube, means for passing molten normally solid heating liquid longitudinally along the outside of said tube, a member extending longitudinally inside said tube and spaced therefrom, means for passing oil through the space between said member and tube, and means mounting said member for adjustment to vary the transverse dimensions of said space.

10. An oil cracking unit comprising an elongated horizontally extending tube, chambers connected to the ends of said tube, means for externally heating said tube, a hollow tubular member extending longitudinally inside said tube and spaced therefrom, means for passing oil from one of said chambers through the space between said member and tube into the other of said chambers, means for removing vapors from one of said chambers, and means mounting said member for adjustment vertically within said tube to vary the spacing of the member from the bottom portion of the tube.

11. An oil cracking unit comprising an elongated horizontally extending tube, chambers connected to the ends of said tube, means for externally heating said tube, a hollow tubular member extending longitudinally inside said tube and spaced therefrom, means for passing oil from one of said chambers through the space between said member and tube into the other of said chambers, means vertically supporting said member within the tube, means for removing vapors from one of said chambers, and means mounting said member for adjustment vertically within said tube to vary the spacing of the member from the bottom portion of the tube.

12. An oil cracking unit comprising an elongated horizontally extending tube, chambers connected to the ends of said tube, means for externally heating said tube, a hollow tubular member extending longitudinally inside said tube and

spaced therefrom, means for passing oil from one of said chambers through the space between said member and tube into the other of said chambers, means for removing vapors from one of said chambers, and means cooperable with an end portion of said member within one of the chambers for adjusting the position of said member vertically within the tube.

13. An oil cracking unit comprising an elongated horizontally extending tube, chambers connected to the ends of said tube, means for externally heating said tube, a hollow tubular member extending longitudinally inside said tube and spaced therefrom, means for passing oil from one of said chambers through the space between said member and tube into the other of said chambers, means for removing vapors from one of said chambers, and means cooperable with an end portion of said member within one of the chambers for adjusting the position of said member vertically within the tube.

14. An oil cracking unit comprising an elongated horizontally extending tube, chambers connected to the ends of said tube, a heat conducting fluid jacket carried by the lower portion only of the tube, a hollow tubular member extending longitudinally inside said tube and spaced therefrom, means for passing oil from one of said chambers through the space between said member and tube into the other of said chambers, means for removing vapors from one of said chambers, and means cooperable with an end portion of said member within one of the chambers and operable from the outside thereof to adjust the position of said member vertically within the chamber.

15. An oil cracking unit comprising an elongated horizontally extending tube, chambers connected to the ends of said tube, means for externally heating said tube, a hollow tubular member extending longitudinally inside said tube and spaced therefrom, means for passing oil from one of said chambers through the space between said member and tube into the other of said chambers, means for removing vapors from one of said chambers, and means cooperable with an end portion of said member within one of the chambers and operable from the outside thereof to adjust the position of said member vertically within the chamber.

NATHANIEL O. HARMON.
